(57) CLAIM

The ornamental design for an electronic device, as shown and described.

DESCRIPTION

FIG. 1 is a top, front, right perspective view of an electronic device showing our new design;

FIG. 2 is a top view thereof;

FIG. 3 is a bottom view thereof;

FIG. 4 is a rear view thereof;

FIG. 5 is a front view thereof;

FIG. 6 is a right side view thereof; and,

FIG. 7 is a left side view thereof.

The broken lines are for the purpose of illustrating portions of the electronic device and form no part of the claimed design. The dotted lines indicate unclaimed boundaries.

The relatively light shade lines on the surface portions indicate claimed regions.
